Antenna arrays or curtains built up of an alignment of elementary sources provide high directivity, while using only easily operated elements.

It is known to cause the plane of maximum radiation of the antenna to be rotated by feeding the elementary sources with suitably adjusted phases, without mechanical rotation of the antenna. To this end, use is made of adjustable phase shifters.

The arrangements used to this end, for example those comprising ferrites, give satisfactory results at the transmission. But at the reception, their high noise level is a drawback which adversely affects their use with highly sensitive receivers.

The elements of the antenna can also be operated with phase shifters, which are preadjusted, the phase variation being obtained by altering the frequency of the wave.

However, this solution is difficult to apply when the received wave has a fixed frequency. Mixers are to be provided for obtaining the difference of the signal frequency and of the frequency of a variable frequency wave, supplied by a local oscillator. This comes back to the drawback mentioned above, for it is difficult to build mixers with very low noise.

It is an object of the present invention to provide an antenna, more particularly for the reception of signals over a wide frequency band, with an adjustable plane of maximum directivity and a very high signal-to-noise ratio.

The antenna array according to the invention is of the type the elementary radiators of which are associated with preadjusted phase shifters, the phase shift obtained being varied by altering the frequency of the wave propagating therethrough.

This antenna is more particularly characterized in that (a) the phase shifters are of two kinds, some of them receiving a variable frequency local wave, while others receive the wave resulting from the mixing of this local wave with the received signal, and (b) the mixers which supply this latter wave are preferably amplifiers of the parametric type including, for example, diodes, tunnel diodes, ferro-electric devices, etc., the local oscillator being the pump oscillator, whose frequency is controlled by the signal if the latter has a variable frequency.

The invention will be better understood from the following description and appended drawings, wherein:

FIG. 1 is a simplified circuit diagram of the arrangement according to the invention;

FIG. 2 shows diagrammatically the circuit of a parametric amplifier;

FIG. 3 shows diagrammatically one embodiment of the invention;

FIG. 4 shows a further embodiment of the invention; and

FIG. 5 is an explanatory diagram of FIG. 4.

The arrangement of FIG. 1 includes n antenna elements or radiators $A_1, A_2, A_3 \dots A_n$. Each radiator receives the signal at frequency f_s and feeds a mixer amplifier M_1 to M_n . A local oscillator G supplies a local wave at a variable frequency f_p . This wave is directly applied to the second input of mixer M_1 , through an adjustable phase shifter P_1 to mixer M_2 , through phase shifters P_1 and

2

P_2 to mixer M_3 and through phase shifters $P_1, P_2 \dots P_{n-1}$ to mixer M_n .

Receiver R receives the wave at frequency f_i which results from the mixing of waves f_p and f_s in mixers M_1 to M_n . The wave from a mixer M_n passes through adjustable phase shifters I_1 to I_n . One has:

$$f_i = f_p - f_s \quad (1)$$

Let d_s be the distance between two antenna elements A_i and A_{i+1} and let θ the angle of the direction of maximum directivity of the antenna array with the normal to the array, i.e. such a direction that the signals, respectively received by receiver R from the elementary radiators A_1 to A_n through mixers $M_1 \dots M_n$ and phase shifters $I_1 \dots I_n$ are all in phase.

The phase difference between the waves received by antennas A_1 and antenna A_{i-1} is:

$$\varphi_1 = \frac{2\pi d_s \sin \theta}{\lambda_s} \cdot \sin \theta \quad (2)$$

where λ_s is the operating wavelength.

The phase at the output of a mixer M_i is the difference between the phase φ_{p_i} of the wave which has propagated through phase shifters P_1 to P_{i-1} and the phase φ_i of the wave propagating from antenna A_i . The wave from antenna A_{i-1} arriving to the receiver is therefore shifted in phase with respect to the wave from antenna A_i by

$$\Delta \varphi_p = \frac{2\pi d_s \sin \theta}{\lambda} - \Delta \varphi_i - 2K\pi \quad (30)$$

where K is an integer and $\Delta \varphi_i$ is the phase shift due to each phase shifter I , and $\Delta \varphi_p$ is the phase shift due to each phase shifter P .

Waves originating from radiators A_{i-1} and A_i will be in phase if:

$$\Delta \varphi_p - \Delta \varphi_i = \frac{2\pi d_s \sin \theta}{\lambda_s} + 2K\pi \quad (3)$$

Preferably, phase shifters P and I are transmission lines, line P all having a length l_p and lines I a length l_i :

Relation 3 can then be written:

$$f_p l_p - f_i l_i = f_s \cdot d_s \sin \theta + nc \quad (3a)$$

where n is a whole member, and c is the velocity of light.

This relation can be written, taking Relation 1 into account:

$$f_p = \frac{l_i - d_s \sin \theta}{l_i - l_p} f_s + \frac{nc}{l_i - l_p} \quad (4)$$

This relation gives the pump frequency f_p to be used for the reception of a wave of frequency f_s propagated in direction θ , with l_i and l_p chosen once for all.

The lengths l_s and l_i may be chosen to secure optimum performance of the amplifier phase shifters.

This statement can be justified by a very simple calculation. The case will be described in which mixers M are parametric amplifiers comprising non-linear capacitors, a similar calculation being possible with a non-linear inductance or resistance elements (for example, a tunnel diode biased close to peak tunnel current).

FIG. 2 shows an equivalent circuit of a parametric amplifier performing the function of the mixers shown in FIGURE 1.

The signal input circuit, the output or idler circuit, and the pump circuit are coupled to each other by a non-linear capacity.

The input and pump circuits include respectively voltage sources V_s and V_p , resistances R_s and R_p and inductance coils L_s and L_p used to tune these circuits respectively to frequencies F_s and F_p . The Q-factors of these circuits will be designated by Q_s and Q_p . The idler circuit is tuned to a frequency $F_i = F_p - F_s$ by an inductance

coil L_i with a Q-factor Q_i and includes a lead resistance R_i .

Under the action of the pump, capacitor C changes its value from C_0 to:

$$C = C_0 + \Delta C \cos(2\pi f_p \cdot t) \quad (5)$$

If a signal of frequency f_s is injected in the signal input circuit, a signal is collected in the idler circuit having a frequency $f_i = f_p - f_s$. It is assumed that the signal has an instantaneous frequency f_s , the pump a variable instantaneous frequency f_p , the pump a variable instantaneous frequency f_i , the resulting idler frequency being f_i .

Setting:

$$f_i = F_i + \Delta f_i \quad \text{with} \quad \epsilon_i = \frac{\Delta f_i}{F_i} \quad (10)$$

$$f_p = F_p + \Delta f_p \quad \epsilon_p = \frac{\Delta f_p}{F_p} \quad (11)$$

$$f_s = F_s + \Delta f_s \quad \epsilon_s = \frac{\Delta f_s}{F_s} \quad (12)$$

F_s , F_p and F_i being the central frequencies to which the three circuits are tuned and Δf_s , Δf_p and Δf_i being the respective instantaneous frequency shifts from said central frequencies.

It is known that, disregarding the diode internal resistance, the conversion gain of a parametric amplifier, that is to say that the ratio of the power collected in resistance R_i to the maximum power available at the signal input, can be written:

$$G = 4 \frac{F_s}{F_i} \frac{\alpha}{(1-\alpha)^2 + (Q_s \epsilon_s - Q_i \epsilon_i)^2} \quad (6)$$

where α is a factor characteristic of the amplifier. Thus:

$$\alpha = Q_s Q_i \left(\frac{\Delta C}{2 C_0} \right)^2 \quad (7)$$

Formula 5 shows that the conversion gain is maximum when α is not close to 1, and

$$Q_s \epsilon_s - Q_i \epsilon_i = 0 \quad (8)$$

i.e. when

$$\frac{\Delta f_s}{\Delta f_i} = K = \frac{F_s}{F_i} \quad (9)$$

where

$$K = \frac{Q_i}{Q_s} \quad (10)$$

Condition 9 shows that the relative mistuning of frequencies f_s and f_i must in this case be mutually proportional to secure optimum performance of the mixer amplifiers, when f_s varies. This relation, which is very simple in the case of simple tank circuits, may be much more complex in the case of actual circuits, but it gives a fair account of the physical phenomena.

The two following cases of operation of the system according to the invention will be considered:

(a) Reception in a fixed direction (for the sake of simplicity, θ will be taken equal to 0) of a signal at an instantaneous frequency f_s deviating by an appreciable amount Δf_s from the central tuning F_s of the diode signal circuit.

The following calculation will show that, for given parametric diodes, l_p and l_i can be chosen to secure optimum gain and minimum noise figure over a relatively wide frequency band $F = F_s \pm \Delta F_s$. Relation 3a becomes:

$$(F_p + \Delta f_p) l_p = (F_i + \Delta f_i) l_i + nc \quad (10)$$

where $\theta = 0$.

This relation must of course apply when Δf_p and Δf_i have the value 0, i.e. in the middle of the band, hence:

$$F_p l_p = (F_p - F_s) l_i + nc \quad (11)$$

subtracting term by term Equation 11 from Equation 10, one may write:

$$\frac{l_i}{l_p} = 1 + K \frac{F_s}{F_i} \quad (12)$$

Equations 11 and 12 with two unknowns l_i and l_p give the relative phase shifts to be applied to phase shifters I and P, in order to obtain, in the case of given parametric diodes, the widest possible reception frequency range with a constant gain:

$$l_p = \frac{n}{1-K} \cdot \lambda_s \quad (13)$$

$$l_i = \frac{n}{1-K} \cdot \lambda_s \left(1 + \frac{K F_s}{F_p - F_s} \right)$$

(b) Reception from a variable direction θ , for a given signal frequency f_s . In this case it is assumed that f_s is fixed, f_p is assumed to vary about the central frequency F_p by an amount Δf_p .

Then $\Delta f_p = \Delta f_i$ and Equation 3a becomes:

$$l_p \Delta f_p - l_i \Delta f_i = f_s d_s \sin \theta \quad (14)$$

Replacing l_p and l_i by their values from Equation 13 and taking into consideration the fact that $\Delta f_p = \Delta f_i$, then:

$$\Delta f_p = -\frac{f_s d_s}{n \lambda_s} \frac{F_s}{F_p - F_s} \sin \theta \quad (15)$$

In order to remain within maximum amplitude conditions, when the direction of maximum directivity is varied by a given value θ , the pump frequency f_p has to be varied by a small amount Δf_p , so that n has to be large. But there is a restriction due to the antenna bandwidth which decreases as n increases.

FIG. 3 shows an embodiment of the invention.

In this figure the same references designate the same parts as in FIG. 1, but now the receiver R is tuned to the signal frequency f_s .

The system includes in addition: A converter M feeding the receiver R for converting the frequency f_i to the signal frequency f_s .

A wavemeter O for measuring the frequency f_s and extracting a voltage V_s proportional to f_s .

An angle computer N supplying a voltage V_θ proportional to θ , the angle to be explored.

A computer C which receives the voltage V_s , V_θ and delivers a voltage V_p which controls the generator G, the latter delivering a voltage f_p in accordance with Relation 4. This is a control system of the phase-lock type which will require search scanning to lock onto an unknown variable frequency. A control for the angle computer can also be envisaged to enable the antenna to follow the direction θ_M of maximum reception. To this end a feedback connection is provided between the receiver R and a control input of computer N.

FIG. 4 shows one other embodiment of the invention.

Source Γ transmits a frequency spectrum as shown in FIGURE 5, the medium frequency of which is a frequency F . A square wave modulated single side band generator may be used for generating said spectrum.

The frequencies f_{p_n} are equally spaced in said spectrum.

The device shown in FIGURE 4 allows the reception in directions θ_n satisfying the following equations:

$$f_{p_n} = \frac{l_i - d_s \sin \theta_n}{l_i - l_p} f_s + \frac{nc}{l_i - l_p}$$

(FIG. 5). The reception along one of said directions is obtained by tuning the receiver to the corresponding idler frequency.

Of course, the invention is not limited to the embodiments shown and described which were given solely by way of example.

What is claimed is:

1. An antenna for ultra-high frequency energy signals comprising in combination: an array of elementary radi-

ators equally spaced along at least one straight line; a plurality of parametric amplifiers having respective first inputs connected to said radiators, second inputs and outputs; a source of a pumping energy; a first plurality of phase shifters having the same predetermined electrical length, connecting in cascade said second inputs to said pumping source; a receiver tuned to an idler frequency of said parametric amplifier; and a second plurality of phase shifters having a second predetermined electrical length connecting in cascade said outputs to said receiver.

2. An antenna for ultra-high frequency signals comprising in combination: an array of radiating elements equally spaced along at least one straight line; a plurality of mixers having respective first inputs connected to said elements, and second inputs and outputs; a source of local energy; a first plurality of phase shifters having the same predetermined electrical length, for connecting in cascade said second inputs to said local source; a receiver tuned at the output frequency of said mixer; and a second plurality of phase shifters having a second predetermined electrical length for connecting in cascade said outputs to said receiver.

3. An antenna for ultra-high frequency energy signals comprising in combination: an array of elementary radiators equally spaced along at least one straight line; a plurality of parametric amplifiers having respective first inputs connected to said radiators, second inputs and outputs; a source of a pumping energy; a first plurality of phase shifters having the same predetermined electric length, connecting in cascade said second inputs to said pumping source; a receiver tuned to the signal frequency and comprising a converter tuned to an idler frequency of said parametric amplifier; a second plurality of phase shifters having a second predetermined electrical length connecting in cascade said outputs to said receiver; and means controlled by said signal frequency for controlling the frequency of said pumping energy.

4. An antenna for ultra-high frequency energy signals comprising in combination: an array of elementary radiators equally spaced along at least one straight line; a plurality of parametric amplifiers having respective first inputs connected to said radiators, second inputs and outputs; a source of a pumping energy; a first plurality of transmission lines having the same predetermined electrical length, connecting in cascade said second inputs to said pumping source; a receiver tuned to an idler frequency of said parametric amplifier; and a second plurality of transmission lines having a second predetermined electrical length connecting in cascade said outputs to said receiver.

5. An antenna for ultra-high frequency energy signals

comprising in combination: an array of elementary radiators equally spaced along at least one straight line; a plurality of parametric amplifiers having respective first inputs connected to said radiators, second inputs and outputs; a source of a pumping energy; a first plurality of transmission lines having the same predetermined electrical length, connecting in cascade said second inputs to said pumping source; a receiver tuned to the signal frequency and comprising a converter tuned to an idler frequency of said parametric amplifier; and a second plurality of transmission lines having a second predetermined electrical length connecting in cascade said outputs to said receiver; a wavemeter coupled to said converter for measuring the signal frequency and for delivering a first voltage proportional to said signal frequency; first computer means receiving a magnitude proportional to the angle of a predetermined directivity, and having an output for delivering a voltage proportional to said angle; second computer means for receiving said first and second voltage and for delivering a control voltage; and means for delivering said control voltage to said source of pumping energy.

6. An antenna for ultra-high frequency energy signals comprising in combination: an array of elementary radiators equally spaced along at least one straight line; a plurality of parametric amplifiers having respective first inputs connected to said radiators, second inputs and outputs; a source of a pumping energy, said source simultaneously generating a plurality of pumping frequencies equally spaced in a predetermined frequency band; a first plurality of transmission lines having the same predetermined electrical length, connecting in cascade said second inputs to said pumping source; a receiver tuned to an idler frequency of said parametric amplifier; and a second plurality of transmission lines having a second predetermined electrical length connecting in cascade said outputs to said receiver.
